SHOE

Sol J. Waxelbaum, Atlanta, Ga.

Application April 4, 1936, Serial No. 72,696

4 Claims. (Cl. 36—11.5)

This invention relates to shoes, particularly shoes of the sandal type having an upper comprising separate forepart and rear portions. The invention has for its principal objects to provide 5 a shoe of the above type having an extremely flexible, light weight forepart that will readily conform itself to the foot and to simplify the manufacturing operation. The invention consists in the shoe and in the process hereinafter 10 described and claimed.

In the accompanying drawings, which form part of this specification and wherein like symbols refer to like parts wherever they occur,

Fig. 1 is a top view of an outsole of a sandal 15 embodying my invention.

Fig. 2 is a fragmentary section through the forepart of said outsole on the line 2—2 of Fig. 1.

Fig. 3 is a face view of the strip for securing the forepart of the upper to the forepart of the outsole,

Fig. 4 is a cross-section through said strip on the line 4—4 of Fig. 3.

Fig. 5 is a top view of the forepart portion of the upper,

Fig. 6 is a vertical longitudinal section on the line 6—6 of Fig. 5.

Fig. 7 is a section similar to Fig. 2, showing the upper securing strip attached to the forepart of the outsole,

Fig. 8 is a top view of the assembled outsole securing strip and forepart upper section,

Fig. 9 is an enlarged fragmentary top view of the toe portion of the assembly shown in Fig. 8.

Fig. 10 is a vertical cross-section on the line 35 10—10 in Fig. 9.

Fig. 11 is a vertical cross-section on the line 11—11 in Fig. 9.

Fig. 12 is a perspective view of one of a series of tabs, forming a modified arrangement for securing the forepart of the upper to the forepart of the outsole,

Fig. 13 is a section similar to Fig. 7, showing the tab of Fig. 12 secured to the outsole,

Fig. 14 is a view similar to Figs. 7 and 13 showing another modified arrangement for securing the securing strip or tabs to the outsole,

Fig. 15 is a bottom plan view of a last, showing the shank piece secured to the rear portion of said last and a metal shank stiffener secured to said shank piece,

Fig. 16 is a view similar to Fig. 15 showing the rear portion of the upper lasted to said shank piece,

Fig. 17 is a vertical longitudinal section on the 55 line 17—17 in Fig. 16.

Fig. 18 is a section with the outsole laid over the shank piece and the bottom of the last and with the forepart of the upper slipped over the forepart of the last,

Fig. 19 is a side elevation of the finished sandal 5 with the sock lining therein,

Fig. 20 is a side elevation of a sandal of modified construction,

Fig. 21 is a fragmentary vertical section on the line 21—21 in Fig. 20,

Fig. 22 is an enlarged edge view of the forepart of the outsole of the sandal shown in Fig. 20 in the region of one of the fasteners for the forepart of the upper; and

Figs. 23 and 24 are a vertical section and an 15 edge view, respectively, of an outsole provided with another modified form of upper fastener.

My shoe or sandal comprises an outsole A, a heel B, a shank piece or rear insole member C, separate forepart and rear upper portions D and E, respectively, a metal shank stiffener F interposed between the outsole and the shank piece, and a sock lining G that covers the shank piece and forepart of the outsole. The upper portion of the outsole A is cut away or rabbeted, as at 20 I around the forepart thereof to receive the marginal portions of a longitudinal folded strip 2, said marginal portions being secured together and to the bottom of the rabbet by means of stitching 3. The strip 2 is notched along its folded free outer margin to form a series of tabs or loops 4 that are spaced apart longitudinally of said strip preferably from end to end thereof.

The forepart D of the upper is provided along its lower margin with a series of similarly spaced 25 tabs or loops 5 that extend into the spaces between the marginal tabs or loops 4 of the strip 2.

The tabs or loops of the strip 2 and the forepart D of the upper are loosely secured together by means of a cord 6, which extends loosely through 30 said tabs or loops and has its ends sewed or otherwise anchored, as at 7, to the outsole, thereby

forming a hinge slip joint between said forepart of said upper and the forepart of said outsole.

In some cases, it may be desirable to secure the 45 forepart of the upper to the insole by means of a series of separate folded tabs or loops 4a like the tab shown in Figs. 12 and 13. The tab or loop may be secured by stitching 3a to the top of the outsole without rabbeting; and the bottom of the 50 outsole may be slit along its edge to provide a flap 8 for concealing said stitching. As shown in Fig.

14, the strip or separate tab or loops 4b may be secured to the outsole by rivets 9 and the heads at the lower ends of the rivets covered by a flap 55

8a similar to the flap 8 shown in Fig. 13. In the modified construction shown in Figs. 20 and 22, the forepart of the upper comprises crossed strips or lacing 16 whose ends are doubled back and inserted within staples 4c that are driven into the margin of the outsole and serve to clamp the doubled-back end portions of the lacing thereto. As shown in Figs. 23 and 24, a pin 8a extends through or over the doubled-back end of the cross strap of the upper and with its ends supported in openings provided therefor in heads formed integral with a pair of spaced rivets 4d embedded in the outsole.

In the process of manufacturing the hereinbefore described sandal, the shank piece C is mounted on a last H, the metal shank stiffener F is secured on top of the shank piece, the rear portion or section E of the upper is pulled over the margin of the rear portion of the shank piece 20 and tacked or otherwise secured thereto. The outsole A with the forepart D of the upper attached thereto in the manner hereinbefore described, is mounted on the last and either permanently cemented to the upper and shank piece 25 or temporarily cemented and sewed in place after the last is pulled. The shank piece and exposed forepart of the outsole are then covered with the sock lining G.

The hereinbefore described arrangement provides a hinge slip joint between the forepart of the upper and the forepart of the outsole that permits relative movement of the outsole and upper in all directions and thus enables the upper to conform to the foot. The sandal is without 30 an insole in its forepart, thereby reducing the weight of the sandal and increasing the flexibility of the forepart of the outsole. The forepart of the upper can be made larger or smaller by slackening or tightening the securing cord. The 35 hereinbefore described process of making the sandal is simple and inexpensive compared with the process of making turned shoes and processes that use temporary insoles in the forepart of the shoe.

40 45 What I claim is:

1. A shoe comprising an outsole, an insole extending from the heel of said outsole only to the ball thereof, and an upper comprising a separate rear portion with its lower margin interposed between and secured to said insole and said outsole and a separate forepart having its lower margin connected to the forepart only of said outsole by a hinge slip joint adapted to permit relative bodily movement of the forepart and rear portions 50 55 of said upper and said forepart portion of said upper and said outsole in all directions.

2. A shoe comprising an outsole, an insole ex-

tending from the heel of said outsole only to the ball thereof, and an upper comprising a separate rear portion with its lower margin interposed between and secured to said insole and said outsole and a separate forepart having its lower margin 5 connected to the forepart only of said outsole by a hinge slip joint, said hinge slip joint comprising a longitudinally folded strip whose marginal portions are secured together and to the top only of said outsole around the margin of the forepart thereof and provided with a series of loops spaced apart along its outer margin, a series of loops formed integral with and spaced apart along the lower margin of the forepart of said upper and disposed loosely between the loops of 10 the strip secured to said outsole, and a flexible member passing loosely through the loops of said forepart of said upper and said strip with its ends anchored to one of said upper forepart and said strip.

3. A shoe comprising an outsole, an insole extending from the heel of said outsole only to the ball thereof, and an upper comprising a separate rear portion with its lower margin interposed between and secured to said insole and said outsole and a separate forepart having its lower margin connected to the forepart only of said outsole by a hinge slip joint, said hinge slip joint comprising a series of spaced looped tabs with their ends secured together and to the top 20 only of said outsole around the margin of the forepart thereof and a similar series of looped tabs formed integral with the lower margin of the forepart of said upper and extending loosely into the spaces between the tabs on said outsole, and a flexible member extending loosely through the looped tabs of said outsole and said forepart with its ends anchored to said outsole.

4. A shoe comprising an outsole, an insole extending from the heel of said outsole only to the ball thereof, and an upper comprising a rear portion with its lower margin interposed between and secured to said insole and said outsole and a forepart having its lower margin connected to the forepart of said outsole by a hinge slip joint, said hinge slip joint comprising a series of metal members spaced apart around the forepart thereof and having openings extending therethrough, rivets securing said metal members flatwise to the upper surface only of said outsole, looped tabs along the lower edge of the forepart of said upper extending loosely into the spaces between said metal members and a member extending through the openings in said metal members and loosely through the loops in the tabs of 40 45 50 55 said forepart of said upper.

SOL J. WAXELBAUM.
